UNITED STATES PATENT OFFICE.

JOSEPH W. DOUGLAS, OF MIDDLETOWN, CONNECTICUT, ASSIGNOR TO
W. & B. DOUGLAS, OF SAME PLACE.

IMPROVEMENT IN PUMPS.

Specification forming part of Letters Patent No. **56,671**, dated July 24, 1866.

To all whom it may concern:

Be it known that I, JOSEPH W. DOUGLAS, of Middletown, in the county of Middlesex and State of Connecticut, have invented a new and useful Improvement in Pumps; and I do hereby declare that the following is a full, clear, and exact description thereof, which will enable others skilled in the art to make and use the same, reference being had to the accompanying drawings, forming a part of this specification, in which—

Figure 1 is an axial section of a pump made according to my invention. Fig. 2 is a peripheral view, the side chamber being presented toward the observer.

Similar letters of reference indicate like parts.

This invention enables one to produce a double-acting pump with only one side pipe. The piston-rod is hollow and receives the liquid which is forced upward through the piston, while the liquid which enters the pump-cylinder through the side pipe is received in the top of the piston and is forced thence through the piston-rod to the top of the pump.

The letter A designates the barrel of the pump, having at one side a pipe or channel, I, which extends in length from the level of the lower or stationary valves up to the top of the cylinder L, in which the piston works, into which cylinder the top of the side pipe is conducted just above the line reached by the upward stroke of the piston.

The bottom of the cylinder L and the bottom of the side pipe have induction-valves J J', through which they communicate with the induction-pipe K, that leads down to the water.

The piston-rod B is hollow and open at its top, and also at its lower end, where it is connected to the neck of the piston G.

The top of the cylinder of the pump is composed of a conically-shaped diaphragm, D, whose lower part has a circular flange, which is clamped between that section of the barrel which composes the cylinder and the section next above at their joint F, the joint being made tight by a packing-ring, E.

The piston-rod B goes through the upper end of the conical diaphragm D, and is free to be moved up and down in it. The upper

end of the piston-rod is enlarged, as at B', so as to touch the interior of the barrel, the lower corner of the enlarged part B' being perforated, as seen at C C, to establish communication between the interior of said part B' of the piston and that part of barrel A which is above diaphragm D.

The piston G has two valve-seats within it, which are made around the induction-passage in the bottom of the piston and the eduction-passage in its top, which eduction-passage goes through its neck into the bottom of the piston-rod. The eduction-passage is always open, and the piston-valve H is always in open communication therewith, the top of the valve being also open.

The valve H is guided in the piston by a spindle, d, from the center of its bottom, going through a hole in the bottom of the piston, and by three or more guide-fingers, c, that rise from the edge of the opening in the top of the valve and enter the neck of the piston. The piston has also induction-openings b in its upper side, arranged around its neck, to establish communication between the interior of the piston and the upper part of the cylinder L.

The upper and lower induction-openings of the piston are closed respectively by the valve-surfaces a a', on the upper and lower sides of the valve.

In operating the pump the descent of the piston causes the valve H to rise and close the induction-openings b, leaving the lower induction-passages open, when the piston is free to pass downward in the cylinder through any liquid which may be found therein. In the upward stroke the valve H falls to the bottom of the piston and prevents the return of the liquid, such liquid being lifted along with the piston, and the valve J, in the side pipe, I, being closed at the same time, because the dropping of the valve H opens communication between the interior of the piston, the top part of the cylinder L, and side pipe, I.

The valve J will be opened when the piston rises by reason of the creation of a partial vacuum in the lower part of cylinder L, which will become filled with liquid through pipe K. On the next descent of the piston, the valve H being thrown up so as to close the openings b, a partial vacuum will be formed in the upper

part of cylinder L and in the side pipe, I, when the valve J' will be forced open by pressure from below and the liquid will rush in from pipe K. When the piston is again drawn upward the valve J, will be closed and the liquid in the upper part of cylinder L being free to enter the piston, will be forced upward through the piston and out of the pump. The conical diaphragm D will be constantly surrounded by liquid, and the joint, where the piston-rod passes through it, is consequently made tight by a liquid packing, which is easily displaced before the descent of the piston, by reason of the openings C in the corner of the enlargement B'.

It results from this construction that I pro-

duce a double-acting pump with only one side pipe.

What I claim as new, and desire to secure by Letters Patent, is—

The combination of the diaphragm D, hollow piston-rod B, having a perforated enlargement, B', and piston G, as described, valve H, with its spindle d and guide-fingers e, cylinder L, and side pipe, I, provided with valves J and J', all arranged and operating substantially as described, for the purpose specified.

JOS. W. DOUGLAS.
